TOWEL RACK

Julius Hurwitz, Bayside, N. Y.

Application January 9, 1956, Serial No. 39,662

Term of patent 7 years

(Cl. D4—3)

Fig. 1 is a front elevational view of a towel rack, showing my new design;

Fig. 2 is a top plan view of the left hand member of the rack;

Fig. 3 is an end elevational view of Fig. 2, taken from the right; and

Fig. 4 is an opposite end elevational view thereof, taken from the left.

The dominant features of the design are shown in full lines.

I claim:

The ornamental design for a towel rack, as shown and described.
